[57] CLAIM

The ornamental design for a combined food slicer and shredder, as shown and described.

DESCRIPTION

FIG. 1 is a front and top-right perspective view of a combined food slicer and shredder showing my new design;

FIG. 2 is a bottom plan view thereof;

FIG. 3 is a top plan view thereof;

FIG. 4 is a front elevational view thereof;

FIG. 5 is a left side elevational view thereof, the right side being a mirror image; and

FIG. 6 is a rear elevational view thereof.

FIG. 1

FIG. 2

FIG. 3

FIG. 6

FIG. 5

FIG. 4
